By Attorney # UNITED STATES PATENT OFFICE.

IRVIN D. LENGEL, OF READING, PENNSYLVANIA, ASSIGNOR TO THE PACKER CYCLE COMPANY, OF SAME PLACE.

DESIGN FOR A CRANK-AXLE HANGER FOR BICYCLES.

SPECIFICATION forming part of Design No. 26,341, dated November 24, 1896.

Application filed September 22, 1896. Serial No. 606,682. Term of patent 34 years.

To all whom it may concern:

Be it known that I, IRVIN D. LENGEL, a citizen of the United States, residing at Reading, in the county of Berks and State of Pennsylvania, have invented a new and original Design for Crank-Axle Hangers for Bicycles; and I do hereby declare the following to be a full, clear, and exact description of the invention.

10 This invention relates to a new and original design for crank-axle hangers for bicycles.

In the drawings, Figure 1 is a plan view of the hanger. Fig. 2 is a sectional view on line *x x* of Fig. 1.

15 A is the barrel of the hanger, provided with a rearwardly-extended tube-bar portion B,

terminating in two branches *b b'*, forming an approximate Y. The barrel is also provided with a rearwardly-inclined socket C for the seat-post mast and a similar forwardly-inclined socket D for the lower head-tube.

What I claim is—

The design for a crank-axle hanger for bicycles, substantially as herein shown and described.

25 In testimony whereof I affix my signature in presence of two witnesses.

IRVIN D. LENGEL.
